UNITED STATES PATENT OFFICE.

ROBERT DONALD, OF LONDON, ENGLAND.

RESPIRATOR.

1,229,050.

Specification of Letters Patent. Patented June 5, 1917.

Application filed March 29, 1917. Serial No. 158,432.

To all whom it may concern:

Be it known that I, ROBERT DONALD, a subject of His Majesty the King of England, and resident of Highgate Road, in the 5 county of London, Kingdom of England, have invented a certain new and useful Respirator, of which the following is a specification.

This invention relates to respirators or 10 inhalers of the kind that may be fitted with inhalation and exhalation valves.

According to the chief features of the present invention the improved respirator or inhaler comprises a closed bag or bags 15 which may contain filtering substance and chemicals and adapted to be held convenient to the nose and mouth of the wearer and being provided with inhalation connections valved or otherwise leading from the interior of the bag or bags to the nose and optionally with an exhalation mouthpiece and non-return valve leading to the atmosphere.

The bags where two or more are employed may be arranged one within another or otherwise in any convenient manner and may 25 be formed of various materials to suit the various chemicals or other substances for combating various harmful matters, the materials thus being for instance woven or 30 felted fabrics of vegetable, of animal or of mineral fiber, or being molded or otherwise formed sheet material such as rubber or mackintosh or iron or other metal coated if necessary and perforated as required. The 35 filtering substance may serve also to separate and to distend the bags and it may be vegetable or animal or mineral fiber such as cocoanut fiber, coarse sheep's wool, horse-hair, asbestos fiber or the like. The chemicals or other medicaments may be various 40 according to the harmful matters to be combated, *e. g.*, for chlorid, bromin, oxids of nitrogen, carbonyl chlorid and similar gases sodium thiosulfate with an alkali such as sodium 45 bicarbonate. The purified air is conveyed from the innermost or the last bag of the series to the nostrils by a pair of tubes of rubber, metal or the like. The fitting of the tubes to the nostrils may be rendered 50 airtight by the addition of a packing, pneu-

matic or otherwise, or by the addition of the known device of nostril-fitting pieces or by other devices as hereinafter described.

Although with a little practice the mouth may be used as a valve almost automatically, yet as a precaution a mouth-flap with a valve may be added. The mouth-flap may consist of a prolongation of the outer bag as hereinafter described, or it may consist of a suitably formed flap of thin fabric. 55 The exhalation-valve might be of any known type permissible and suitable. But the valve preferably used is formed of a simple thin fabric, that is, of a fabric alone such as oiled silk, mackintosh, rubber or the 60 like, without the adjunct of a stiff valve-seat.

The strap for holding the respirator in position convenient to the mouth and the nose may have a special form; the part that 70 passes over the scalp may consist of a permanent loop one band of which passes behind and the other in front of the occiput.

Above have been described the main features of the respirator; below are given the 75 constructional details of one form of respirator designed for combating such noxious vapors as are antidoted by an alkali or an alkali with an "antichlor".

In the presence of an alkali, vegetable 80 fabric and vegetable fiber are of course used as a filtering and distending substance. Washed unbleached Turkey toweling of linen or of cotton, tried in my earliest experiments were unsurpassed. Of this fabric wet with solution of "hypo" and sodium bicarbonate two layers as bags proved effective in rendering thoroughly unirritating the air breathed in an atmosphere containing at least 5% of bromin.

A respirator of two bags one inside the other is hereinafter described with reference to the accompanying drawings in which:—

Figure 1 is an elevation of this form of 95 respirator as seen from behind.

Fig. 2 is a sectional side elevation of such a respirator showing same applied to the mouth and nose of a wearer;

Fig. 3 is an opened out plan view illus- 100

trating a convenient method of making up the respirator; it shows the two pieces of toweling laid flat the one on the other.

Fig. 4 is a detail view of a shaped nasal connection piece.

Fig. 5 is a similar view of a slightly modified form of nasal fitting;

Fig. 6 is a detail view showing a petticoat valve arranged on one of the nose tubes.

10 Fig. 7 is a detail sectional view of the exhalation valve; and

Fig. 8 is an end elevation of said valve.

As shown a respirator comprising two bags one inside the other is made from two pieces of toweling *a* *b* conveniently about 15 16"x8" and 9"x7" respectively. In the larger piece *a* are formed two holes *a'* *a''* which are reinforced by tape or by buttonholing and are made of a size to grip the 20 rubber tube *c* of the exhalation valve as it passes through the outer bag *a*. To form a sleeve through which fresh antichlor charges may be introduced preferably into the space between the two bags, a piece of 25 unbleached cotton or linen *d* is attached along one edge of the larger piece of toweling *a*, as shown in Figs. 1 and 3. The smaller piece of material *b* has two wedges *e* cut from it to leave, later on, a notch in 30 the lower edge of the sewn up inner bag to allow the exhalation valve *c* as mentioned to pass; also it has a suitable layer of clean cocoanut fiber stitched to its surface that will be the outer surface of the inner bag.

35 This smaller piece of toweling *b* is now laid fiber downward on the larger piece *a* as shown in Fig. 3 and the two pieces are now to be sewn together around a tape patch *f*. In the said patch *f* the two layers 40 of toweling alternate with three pieces of strong tape. In the patch *f* are now punched two holes *g* with a space between them, each hole being in a square of stitching. Through these two holes *g* are passed 45 the two nose tubes *h*. Molded soft rubber nostril pieces *i* and *j* such as shown in Figs. 4 and 5 respectively, may be attached to the rubber metal or like tubes *h*. Fig. 6 illustrates a nostril fitting piece having a 50 disk or washer *k* of thin rubber or other suitable material passed over it so as to form a crinoline or an open umbrella which will press against the inner surface of the nose and act as a valve to prevent the inhalation of untreated or contaminated air.

55 As the finished bag has its fold or upper edge immediately above the taped patch *f* the patch and the nose tubes *h* will when the bag is in position as shown in Fig. 2 60 point backward as well as upward. A petticoat valve as described above may be placed on each tube.

The material *b* forming the inner bag is now sewn up without tape binding. The

outer bag is next, except where the charging sleeve enters, sewn up with a tape binding 6 or 7 inches shorter than the seam would otherwise be, and this gathering up of the material forms, as shown, a pouch for the wearer's chin, which pouch may 70 however be turned inside out if or when desired to leave the mouth more free.

The two taped holes *a'* *a''* for the passage of the exhalation valve *c* may be joined by a short tube *l* of calico or other material 75 to form a complete tube through which the rubber tube *c* containing the valve may pass. Each end of the calico tube is turned back and out and the line of folding is stitched to the tape of the hole. The respirator is finished by sewing on at the level of the lower edge of the finished sleeve *d* the supporting strap *m*, as shown, and its buckle *n*.

When the charge of about an ounce of 85 antichlor mixture is introduced through the charging sleeve *d* the sleeve is tied and tucked in. The bag now needs only wetting before use.

What I claim is:—

1. A respirator comprising a porous bag adapted to contain chemicals for absorbing obnoxious and injurious gases and vapors, tubes leading from the interior of the bag to the nose, an exhalation non-return valve 95 leading to the atmosphere, and a sleeve attached to the bag for the introduction of fresh charges to the same.

2. A respirator comprising a closed porous bag adapted to contain a filtering substance and chemicals adapted to absorb obnoxious and injurious gases and vapors, means for the introduction of fresh charges to the same, tubes leading from the interior of the bag to the nose, and an exhalation 105 non-return valved tube extending through said bag and projecting therefrom at both ends, one end of said tube opening into the atmosphere and the other end being adapted to be supported in the mouth.

3. A respirator comprising inner and outer porous bags adapted to receive between them chemicals for absorbing injurious and obnoxious gases and vapors, and tubes leading from the inner bag through 115 the outer bag to the nose.

4. A respirator comprising inner and outer porous bags adapted to receive between them chemicals for absorbing injurious and obnoxious gases, tubes leading 120 from the inner bag through the outer bag to the nose, a sleeve connected to the outer bag for the introduction of fresh charges between the bags, and an exhalation non-return valved tube extending through the 125 bags and leading to the atmosphere, the outer bag being formed as a pouch or flap to fit the wearer's chin.

5. A respirator comprising inner and outer porous bags adapted to receive between them chemicals for absorbing injurious and obnoxious gases, tubes leading from 5 the inner bag through the outer bag to the nose, and a sleeve connected to the outer bag for the introduction of fresh charges

between the bags, the outer bag being formed with a pouch or flap to fit the wearer's chin.

In testimony whereof I have hereunto signed my name. ¹⁰

ROBERT DONALD.
